UNITED STATES PATENT OFFICE.

BRANCH WATKINS, OF NEWPORT NEWS, VIRGINIA.

SIGNAL DEVICE FOR CARS.

1,334,424.

Specification of Letters Patent. Patented Mar. 23, 1920.

Application filed June 4, 1919. Serial No. 301,699.

To all whom it may concern:

Be it known that I, BRANCH WATKINS, a citizen of the United States, residing at Newport News, in the county of Warwick 5 and State of Virginia, have invented certain new and useful Improvements in Signal Devices for Cars; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this 10 specification.

This invention relates to new and useful improvements in display signals for automobiles, cars, etc., and consists in the provision of a simple and efficient device of this character so arranged that the operator by pulling upon members may cause the door to the casing to open and a paddle to be displayed indicating the movements of the car, as to whether or not same is to turn to the right, 25 left, go ahead, stop and so forth.

The actuating apparatus is so positioned that the signal may be displayed by the occupant within the car, and when the signal is thrown back to its normal position the 30 door will be automatically closed.

My invention comprises further various details of construction, combination and arrangement of parts which will be herein-after fully described, shown in the accompanying drawings and then specifically defined in the appended claims.

I illustrate my invention in the accompanying drawings which, with the letters of reference marked thereon, form a part of 40 this application, and in which:

Figure 1 is a rear view of a car showing the application of my invention.

Fig. 2 is a side elevation.

Fig. 3 is an enlarged detail sectional view, 45 parts shown in elevation.

Fig. 4 is a sectional view on line 4—4 of Fig. 3.

Fig. 5 is a detail sectional view of the paddle actuating mechanism.

Fig. 6 is a detail sectional view.

Fig. 7 is a detail perspective of one of the paddles.

Reference now being had to the details of the drawings by numerals:

55 1 designates an automobile, in connection with which the signal is to be applied. Fas-

tened to a bracket arm 2 at any suitable location, such as the body of the car, is a casing 3, details of which are shown in Figs. 3 to 5 of the drawings (inclusive), and which is secured to said bracket and is adapted to be illuminated by light.

Said casing has a door 6 which is hinged at 7 to the marginal edge of the opening in the casing, and 8 is a rock shaft mounted in the casing and has pivotally mounted thereon a series of collars 9 having integral arms 10, and 11 designates coiled springs connecting the ends of the arms with the casing as shown in Fig. 5 of the drawings. Each collar has fixed thereto a paddle 12 bearing wording thereon such as "Stop," "Right," "Left," "Go ahead," etc., there being a plurality of paddles of similar construction each bearing a distinct word.

The casing 13 carries a series of pull rods 14, each connected through the medium of the cable 15 with an arm 10 and so arranged that when the rod is depressed, the door 6 may be opened and a paddle thrown to horizontal position to display the word indicating the movement of the car. When pressure is relieved from the push rod, the spring will throw the paddle back to normal position and the door will close.

A stop 6 is mounted upon the cable and serves as a means for limiting the movement of the paddle in one direction by coming in contact with the casing in which the cable is mounted.

By the provision of a signal device made in accordance with my invention, it will be noted that a simple and efficient means is afforded whereby the movements of an automobile may be designated by the operator within the car simply by pushing on a button, thus indicating the movements of a car without the necessity of throwing out an arm as is commonly the practice.

The device being simple in construction it may be attached for use upon various makes of cars or vehicles.

What I claim to be new is:

1. A display signal for automobiles consisting of a casing with a hinged door in the side thereof, a rock shaft journaled in the opposite walls thereof and opposite the hinged end of the door and spaced apart therefrom, a collar fixed to said shaft and having an integral arm, a spring fastened at one end to said arm and the other end to the casing above the door, a paddle secured

to the collar, and means fastened to said arm and adapted to swing the paddle to a horizontal position to automatically open the door.

- 5 2. A display signal for automobiles consisting of a casing with a hinged door in the side thereof, a rock shaft journaled in the opposite walls thereof and opposite the hinged end of the door and spaced apart
10 therefrom, a collar fixed to said shaft and having an integral arm, a spring fastened at

one end to said arm and the other end to the casing above the door, a paddle secured to the collar, and means fastened to said arm and adapted to swing the paddle to a horizontal position to automatically open the door, and means for limiting the rocking movement of said shaft when actuated to throw the paddle to displayed position. 15

In testimony whereof I hereunto affix my 20
signature.

BRANCH WATKINS.
